UNITED STATES PATENT OFFICE.

FREDERICK VOGEL, OF NEW YORK, N. Y.

COMBINED HAT-RACK, BLACKING-STAND, &c.

SPECIFICATION forming part of Letters Patent No. 233,580, dated October 19, 1880.

Application filed July 16, 1880. (No model.)

To all whom it may concern:

Be it known that I, FREDERICK VOGEL, a citizen of the United States, residing at New York, in the county and State of New York, 5 have invented new and useful Improvements in Hat-Stands, of which the following is a specification.

My invention relates to an article of furniture the construction of which adapts it to 10 subserve the purposes of a hat-stand, umbrella-holder, and a combined blacking-stand and case for receiving such stand when not in use.

I will first describe the general construction of this article of furniture, and afterward point 15 out by the claim the features of novelty.

In the accompanying drawings, in which similar letters of reference indicate like parts, Figure 1 is a front elevation of my improved hat-stand with the blacking-stand raised up 20 beneath the table. Fig. 2 is a vertical section of the same, and Fig. 3 is a horizontal section on X Y of Fig. 3.

The lower part of the hat-stand consists of a small table, of which *a* is the top. *e* is a 25 drawer.

The upper part of the stand, to which the hooks *h* are attached, is formed of the two sides *b b*, the back *e*, and the hinged or pivoted looking-glass *d*, which together form a small 30 closet, which may be used for various purposes. When this closet is to be used as an umbrella-stand it has at the bottom a water-pan, *p*.

f is a blacking-stand, provided with the usual

appliances. This blacking-stand is hinged to the table-frame by means of links *l* and joints 35 *g* and *i*. By means of one or more cords, *j*, pulleys *k*, and balance-weights *w*, the whole blacking-stand is folded or raised up beneath the table, as shown in full lines in Figs. 1 and 2. The position of the blacking-stand *f* when 40 in use is indicated in dotted lines in Fig. 2. The front of the blacking-stand is made of such a shape as to give an ornamental finish to the combination when the blacking-stand is folded up beneath the table.

m m are water-pans for umbrellas. *n n* are umbrella-guards of the usual construction. The guards *n n* are side extensions of the table *a*, and the base *B* of the casing *B'*, which receives the blacking-stand when the stand is 50 not in use, is recessed at its ends for the pans *m*.

What I claim is—

The combination, with the table *a* at the base of a hat-stand, of the blacking-stand *f*, connected to the frame of said table by pivoted 55 links *l*, and the weighted cord passing over a pulley, *k*, for raising said blacking-stand under the table, substantially as herein shown and described.

In testimony whereof I have hereunto set 60 my hand in the presence of two subscribing witnesses.

F. VOGEL.
